Patented Sept. 29, 1959

186,226

CIRCUIT BOX FOR BOAT INSTRUMENT PANELS

Harold J. Anderson, Kansas City, Mo., assignor to North-east Tool & Die Works, Incorporated, Kansas City, Mo., a corporation of Missouri

Application July 23, 1958, Serial No. 51,904

Term of patent 3½ years

(Cl. D26—13)

Fig. 1.

Fig. 2.

Fig. 3.

Fig. 4.

Fig. 5.

Fig. 1 is a top plan view of a circuit box for boat instrument panels showing my new design;

Fig. 2 is a bottom plan view;

Fig. 3 is a rear elevational view;

Fig. 4 is a front elevational view; and

Fig. 5 is an end elevational view.

I claim:

The ornamental design for a circuit box for boat instrument panels, as shown.
